UNITED STATES PATENT OFFICE.

ALBERT ALLEN, OF BANGOR, MAINE, ASSIGNOR TO EASTERN MANUFACTURING COMPANY, OF BOSTON, MASSACHUSETTS, A CORPORATION OF MASSACHUSETTS.

PROCESS OF WATERMARKING PAPER AND ADJUNCT THEREFOR.

Application filed November 20, 1925. Serial No. 70,284.

To all whom it may concern:

Be it known that I, ALBERT ALLEN, a citizen of the United States, residing at Bangor, in the county of Penobscot and 5 State of Maine, have invented new and useful Improvements in Processes of Watermarking Paper and Adjunct Therefor, of which the following is a specification.

This invention has relation to watermarking bands for mounting on cylinders or rolls, or other similar watermarking contrivances which are employed for impressing marks on a web of paper during the course of its manufacture, and has for its object 10 to provide an adjunct for such devices whereby a pleasingly blurred or indistinct watermark may be produced on the paper, closely simulating the old-fashioned watermark obtained by the use of a dandy roll 15 in connection with a relatively slow rate of paper formation.

Where a dandy roll is employed, it is caused to ride on the web while it is on the Fourdrinier wire and still contains a very 20 large water content. The general use of a dandy roll for effective watermarking is, however, limited because of the largely different speeds at which various paper-making machines are run, since in machines where 25 high paper-making speed is employed, the desirable indistinctness of the mark is accentuated to an unpleasant blur.

In application, Serial No. 8,671, filed jointly Feb. 12, 1925, by Stuart W. Webb 30 and Hugo H. Hanson, there has been disclosed and claimed a method of producing a pleasantly indistinct watermark closely resembling that produced by a dandy roll at low speed, and which may successfully 35 be applied to paper-making machines run at relatively high speeds, by locating the watermarking device at a definite position in the course of the manufacture of the paper, this position being after leaving the Fourdrinier wire and before it reaches the 40 press rolls.

I have discovered that if the watermarking band or equivalent device is covered with a smooth, thin protecting web of suitable 45 material, which may for convenience of designation be termed a membrane, during the impression of the mark, particularly when this band is so located as in the hereinbefore described application for patent, an 50 indistinct watermark which more closely

resembles an old fashioned watermark is produced.

On the accompanying drawings,

Figure 1 represents in detailed perspective 60 a watermarking band which may be applied to a roll or cylinder and which is fitted with a membrane, partly cut away to show the marks on the band.

Figure 2 is a similar view, showing the 65 web or membrane which is employed for covering the watermarking band, partly broken into.

Figure 3 represents a detailed section 70 through a marking portion of the band shown in Figure 1, with the membrane 75 lying thereover.

Referring to the drawings, 1 as a whole represents a watermarking band which is adapted to be mounted on a roll or cylinder. The band, which is preferably made of substantially impervious material as rubber, has raised marking elements 2 thereon, which are to be impressed on the web of paper to form the watermark. The band is provided with a smooth and thin flexible covering 3, 80 which entirely covers or overlies the marking elements 2, as shown in Figure 3. It has been found that most desirable results in watermarking have been effected with thin, smooth, extensible rubber sheeting approximating 5/1000 to 10/1000 of an inch thick. 85 Where the watermarking device is in the form of a band, the sheeting is also preferably formed in the shape of a band, as shown in Figure 2, of somewhat less diameter than the external diameter of watermarking band in connection with which it is to be used. In applying it to the band 1, it is stretched thereover and the thin rubber sheeting assumes somewhat the contour or 90 outline of the marking elements.

In impressing the watermark with the roll on the web of paper, the thin, smooth sheet of covering material 3 acts to round or smooth off the sharp edges of the marking elements, and thus to prevent a sharp, well-defined watermark from being impressed, producing, instead, an indistinct watermark characterized by its indefinite 100 edge lines, which merge into the main body of the paper. Any other suitable protecting thin elastic membrane or film may be employed for the band, which, particularly when located in the position described in the application referred to, has been found to 105 110

produce excellent results. This invention, while especially contemplating the use of the watermarking device in the advantageous position described, is not intended to be limited in its broadest aspects to any particular location thereof.

I am well aware of the fact that it has been proposed to cover the watermarking devices with fabrics to produce a fabric finish on the paper, but in the present instance, it is not desired to produce such an effect.

Having thus described this invention, it should be obvious that changes or modifications might be resorted to without departing from the spirit or scope thereof as defined by the appended claims.

I claim:

1. The combination with a watermarking device having marking elements, of a smooth membrane covering the marking elements on said device.

2. The combination with a watermarking band adapted to be mounted on a cylinder or roll, of a membrane covering the marking portion of said band.

3. The combination with a watermarking device, of a smooth sheeting of thin rubber covering the marking portion of said device.

4. The combination with a watermarking device, of a smooth sheeting of thin rubber, approximating 5/1000 to 10/1000 of an inch thickness, stretched over and covering the marking portion of said device.

5. The combination with a watermarking device, of a smooth sheeting of thin substantially impervious material covering the marking portion of said device and assuming somewhat the contour thereof.

6. A process of watermarking paper in the course of its manufacture, which comprises interposing a smooth membrane between the marking device and the web of unfinished paper on which the mark is to be impressed.

7. A process of watermarking paper in the course of its manufacture, which comprises interposing a smooth sheeting of thin rubber between the marking device and the web of unfinished paper on which the mark is to be impressed.

8. A process of watermarking paper in the course of its manufacture on a Fourdrinier paper-making machine, which consists in subjecting the paper web to a watermarking device having a smooth membrane covering the marking portion of said device, and impressing the mark on the web after it has left the Fourdrinier wire and before it reaches the press rolls.

9. A process of watermarking paper in the course of its manufacture on a Fourdrinier paper-making machine, which consists in subjecting the paper web to a watermarking band provided with a smooth sheeting of thin rubber stretched over and covering the marking portion of said band, and impressing the mark on the paper after it has left the Fourdrinier wire and before it reaches the press rolls.

10. The combination with a watermarking device made of rubber, of a smooth membrane covering the marking portion of said device.

In testimony whereof I have affixed my signature.

ALBERT ALLEN.
